United States Patent

Des. 242,313
Patented Nov. 16, 1976

242,313

BOOKSHELF

Adair C. Stentz, Columbus, Ohio, assignor to The Columbus Show Case Company, Columbus, Ohio

Filed Mar. 17, 1976, Ser. No. 667,671

Term of patent 14 years

Int. Cl. D6—04

U.S. Cl. D6—132

FIG. 1.

FIG. 2.

FIG. 3.

FIG. 4.

FIG. 5.

FIG. 6.

FIG. 7.

FIG. 8.

FIG. 9.

FIG. 10.

FIG. 1 is a perspective view of a bookshelf showing my new design;

FIG. 2 is a front elevational view of FIG. 1;

FIG. 3 is a rear elevational view of FIG. 1;

FIG. 4 is a top plan view of FIG. 1;

FIG. 5 is a side elevational view showing the side opposite that shown in FIG. 1;

FIG. 6 is a perspective view of a modified embodiment of the bookshelf shown in FIG. 1;

FIG. 7 is a front elevational view of FIG. 6;

FIG. 8 is a rear elevational view of FIG. 6;

FIG. 9 is a top plan view of FIG. 6; and

FIG. 10 is a side elevational view showing the side opposite that shown in FIG. 6.

I claim:

The ornamental design for a bookshelf, substantially as shown and described.
